UNITED STATES PATENT OFFICE.

CLARK OLDER, OF PORTAGE, WISCONSIN.

KNITTING-MACHINE AND KNIT FABRIC.

SPECIFICATION forming part of Letters Patent No. 552,583, dated January 7, 1896.

Application filed February 4, 1895. Serial No. 537,241. (No model.)

To all whom it may concern:

Be it known that I, CLARK OLDER, of Portage, in the county of Columbia and State of Wisconsin, have invented a new and useful 5 Improvement in Knitting-Machines and Knit Fabrics, of which the following is a description, reference being had to the accompanying drawings, which are a part of this specification.

10 My invention has relation to improvements in knitting-machines.

The device is adapted to be used with those circular-knitting machines in common use employing a plurality of threads, and in which 15 there is a stationary needle-cylinder, a cam-cylinder revoluble about the needle-cylinder, and vertically-reciprocable needles actuated by the cam-cylinder, the device accomplishing especially satisfactory results with a machine 20 in which the needles alternately have short and long toes actuated by cams, one of which at least, if the cam-cylinder is revolving continuously in one direction, or if oscillating, then when moving in one direction, 25 passing the needles having the short toes without putting them into action.

The primary object is to provide a construction capable of producing a fabric having loose inner loops, whereby said fabric is 30 rendered thicker, warmer, more comfortable, and of better wearing capacity than the ordinary knit goods.

The invention also contemplates as an object means whereby the mechanism for forming the loose loop may be thrown out of action, when desired, for the purpose of forming 35 the ordinary stitch.

With the above and other objects in view the invention consists of the devices and parts, 40 or their equivalents, as hereinafter more fully set forth.

In the accompanying drawings, Figure 1 is an elevation of the device in connection with a needle-cylinder and cam-cylinder of a form 45 now in use. Fig. 2 is a vertical sectional view of the complete device. Fig. 3 is a plan view of the attachment, with a part broken away. Fig. 4 is a plan view of the pin-supporting plate, showing a number of the pins projecting 50 outwardly beyond the edge of the plate and which is the position to which they are forced by the action of the cam. Fig. 5 is an

inverted plan view of the pin-cam casing. Fig. 6 is an elevation of the lower portion of the attachment, showing the needle-cylinder 55 in section and a part of the depending hub of the pin-supporting plate broken away. Fig. 7 is a section on the line 7 7 of Fig. 6. Fig. 8 is an elevation of the pin-cam casing and the pin-supporting plate, showing the 60 slot through which the pins are passed in placing them in proper position. Fig. 9 is a plan view of a form of cam now in use. Fig. 10 is a developed view of Fig. 9. Fig. 11 is a section on the line 11 11 of Fig. 10. Fig. 65 12 is a view, on an enlarged scale and in diagram, showing the different positions of the needles and the pins during the operation of knitting when a cam-cylinder of the form shown in Figs. 1, 9, 10 and 11 is employed. 70 Fig. 13 is an enlarged elevation of a fragment of the knit fabric. Fig. 14 is a plan of Fig. 13. Fig. 15 is an outer face view of a fragment of the cam-cylinder. Fig. 16 is a transverse section of Fig. 15 on the line 16 16. Fig. 75 17 is a view of a fragment of the inner side of the fabric, showing clearly the inner long loops arranged adjacent to each other to form a practically continuous inner lining.

Like numerals and letters of reference refer 80 to like parts throughout the several views.

Referring to the drawings, the numeral 15 indicates a bed-plate having the needle-cylinder 16 projecting upwardly therefrom, in the grooves of which the needles reciprocate 85 vertically. Revolving about the needle-cylinder is the cam-cylinder 17.

The numerals 18 18 indicate standards which at their lower ends are secured rigidly to the cam-cylinder and at their upper ends 90 are connected by a cross-piece 19, which is provided with a central upwardly-extending apertured boss 20. Passing through this apertured boss is a vertical shaft 21, provided with a threaded portion 22, which is adapted 95 to receive a nut 23, which nut rests upon the upper end of the boss, and thereby supports the shaft. The nut is advisably provided with a series of peripheral recesses adapted to receive a suitable turning tool. The upper end of the shaft is reduced to form a spool-spindle 24. The lower end of this spindle is threaded, as indicated at 25, which threaded portion is adapted to engage the threaded

aperture of a spool-supporting plate 26, said plate provided with a projecting arm 27, which arm in turn is provided with a yarn stand or supporter 28.

- 5 Upon the shaft below the cross-piece 19 is a disk 29, said disk being provided with an upwardly-extending integral collar 30, through which a set-screw 31 is passed and by which means the disk is held fast to said shaft.
- 10 The disk is provided with a peripheral notch 32, adapted normally to be engaged by a spring-actuated dog 33 carried by the cross-piece.

Upon the shaft below the disk is a pin-cam 15 casing 34. This casing is provided with an upwardly - extending tubular portion 35 through which a screw 36 is adapted to pass and engage the shaft, whereby the casing is held rigid to the shaft. Secured beneath the 20 casing and against the depending flange 37 thereof are curved outer cam-plates 38. A passage-way 39 is formed in this outer plate, which leads to and registers with a slot 40 in the depending flange of the casing. The inner cam portion is formed of two parts, one of which, 41, is secured rigid in the casing, while the other, 42, is adjustable radially therein. These two sections 41 and 42 are of 25 approximate **U** shape, and the adjustable one 30 is adapted to telescope in the recess 43 of the rigid section. The adjustment is attained by means of a lug 44, secured to the upper side of cam-section 42 and working in a slot 45 for its accommodation in the pin-casing. The 35 lug has secured to its upper side a plate 46, which plate rests upon the upper face of the pin-casing. Projecting from the plate is a stud 47, which stud is adapted to enter an elongated slot 48 in one arm of a pivoted bell-40 crank lever 49, said bell-crank lever being provided with a suitable handle 50 for operating it. The curved edges of the outer cam-plates 38 and the curved edges of the inner cams 41 and 42 form the walls of a cam-slot 51.

45 It will be noticed that when the adjustable part 42 is in the position shown in Fig. 5, which is its normal position, the curved edge of said adjustable part, in connection with the tapering ends of the cam-plates 38, brings the 50 cam-slot at this point much nearer the depending flange 37 than at other points.

Below the casing 34 is a pin-supporting plate 52, provided centrally with a depending-hub 53, through which the shaft passes freely. 55 The lower end of this hub bears against and is supported by a collar 54 held fast to the shaft by means of screws 55 55. The upper face of the plate 52 is provided with a series of radial grooves 56, (see Fig. 4,) in which the pins 57 60 are arranged. When the parts are properly adjusted together, and it is desired to place the pins within the grooves, a convenient way is to pass said pins through the registering slot and passageway 40 and 39, respectively, 65 until the toe 58 of each pin contacts with the inner wall of the cam-slot 51, in which slot the toes ride.

The upper end of the collar 54 is provided with an annular rim or flange 59, having a notch 60 therein, said notch adapted to be engaged by a spring-actuated dog 61, pivoted within the recess of the hub 53, the function of which dog will be hereinafter described.

The needle-cylinder is provided upon its inner side with an inwardly-projecting lug 62, 70 which is adapted to extend into a recess of a part depending from the pin-supporting plate, which lug contacting with the bordering edge of the recess will prevent the turning of the pin-plate. The depending part is preferably 75 formed of two sections. One of these sections 63 depends from and is connected rigidly to the under side of the pin-plate, and the other section 64 is of an approximate inverted **L** shape, with its upper member fitting in a dove-80 tail recess 65 of section 63, and provided with an elongated slot 66 through which a set-screw 67 passes, whereby said member may be adjusted, and the width of the recess into which the lug 62 extends thereby conveniently regulated. As the knit fabric has to pass over the lug 62, it is of course obvious that it is always necessary to have a space between said lug and the walls of the recess. By adjusting the 85 width of this recess it may be made to accommodate itself to different thicknesses of 90 knit fabric.

The numerals 68 68" indicate the needles which reciprocate vertically in the grooves of the needle-cylinder 16, and 69 69' indicate the 100 ordinary guides through which the yarns pass on their way to the needles.

As the standards 18 18 are connected to the cam-cylinder, it is obvious that in the operation of my device said standards are carried 105 around with the cam-cylinder, and in turn carry therewith the connecting cross-piece 19. This cross-piece, through the medium of the dog 33 engaging the notch of the disk 32, causes the shaft 21 to rotate toward the right 110 of Fig. 1. As the shaft is thus rotated it carries with it the pin-cam casing 34, as indicated by the arrow in Fig. 5. In the rotation of the casing in this manner, with the part 42 of the cam at the adjustment indicated in Fig. 5, it 115 is obvious that as fast as the toes of the pin enter the portion of the cam-slot 51 nearest the depending flange 37 said pins will be forced outwardly in the radial grooves 56, and subsequently drawn in again as this portion of 120 the cam-slot leaves them, and so on continuously during the revolution, each separate pin being similarly affected.

As stated at the outset of the specification, a preferred use of my attachment is in connection with machines in which the needles alternately have short and long toes actuated by cams, one of which at least, if the cam-cylinder is revolved continuously in one direction, or if oscillated or reciprocated, then 125 when moved in one direction, passes the needles having short toes without putting them into action. As machines of this character necessarily employ needle-cams of peculiar 130

construction, I have deemed it best, in order to clearly show the application of my device thereto, to illustrate and describe the cam-cylinder and cams employed in such machines, and which are, therefore, shown in Fig. 1, and in detail on Sheet 4. Arranged in connection with the inner face of this cam-cylinder are vertically-movable wedge-shaped stitch-cams 68' 68³ and an annular ledge 69" extending nearly around the whole inner face of the cam-cylinder. The wedge-shaped stitch-cams are attached by the pins 70 70' to blocks 71 71' adapted to slide vertically in suitable slots, one of which slots and the block therein are shown clearly in Fig. 1. The said pins 70 70' project outwardly from the cam-cylinder, and when said cylinder is rotated in either direction one of the pins will ride up an inclined cam 72 and the other down a corresponding inclined cam 72'. These cams are rigid to and project upwardly from a segmental plate 73, which plate rests loosely in an annular groove formed in a ring 74, which latter encircles the outside of the cam-cylinder and is attached to the bed-plate by suitable screws.

Within the space left by the division of the annular ledge 69" and riveted to the cam-cylinder is an inverted-V-shaped plate 75, which constitutes the needle-elevating cam, it being of such size as to leave channels 76 76' between it and the movable stitch-cams 68' 68³ for the passage of the heels of the needles. This plate is made about one-fourth of the thickness of the annular ledge 69" and of the stitch-cams 68' 68³, the difference being approximately the difference between the length of the long-toed needles and the toes, of the short-toed needles.

The plate 75 is provided at opposite edges with diagonal slots 77 77', in which slots slide-pieces 78 and 79, respectively, work, said slide-pieces being actuated by means of nuts 80 80'. Above the plate 75 and the stitch-cams 68' 68³ is arranged the guide-plate 81.

A V-shaped depression 82 is formed in the cam-cylinder in advance of the vertically-movable stitch-cams. In this depression works an auxiliary cam 83, which is attached to a block 84 by means of a pin 85. The block works in a suitable slot therefor in the cam-cylinder, and the pin projects outwardly from the cam-cylinder and enters a head 86. Above one end of the auxiliary cam is a sliding guide-block 87, which is operated by means of a nut 88. This guide-block, when pushed inwardly by pressure on the nut 88, causes the toes of the needles to be caught in the depression 82. When said guide-block is pulled outwardly to bring its end flush with the inner face of the cam-cylinder by a pull on the nut 88 and the cam 83 is depressed by means presently to be described, the needles pass above the upper edge of the cam 83. This nut 88 when operated also acts to operate a pivoted arm 89 by means of a cam-surface 96 formed beneath the shank of the nut. When the nut

is pulled out, it draws the guide-block 87 flush with the inner side of the cam-cylinder, while at the same time the cam 96 allows for the 70 arm 89 turning on its pivot in such manner as to lower the head 86 and the auxiliary cam 83 connected thereto, the lowering of the head being assisted by means of the spring 97. When the nut is pushed in, it is obvious that 75 a reverse operation takes place.

The operation is as follows: In the round-and-round knitting the cam-cylinder and vertical shaft are revolved to the right. In this rotation the stitch-cam 68³ is held in a raised 80 position by its pin 70, said pin having been carried up to the upper end of the cam 72 by the rotation of the cam-cylinder, while the stitch-cam 68' is held in its lowermost position by reason of its pin having been carried 85 to the lower end of the other cam 72'. Of course with the continued rotation of the cam-cylinder the relative position of these parts is not changed, as the pin 70 of stitch-cam 68³ produces sufficient friction on its cam 72 90 to carry the segmental plate 73 around with the cam-cylinder. In this round-and-round knitting it will be understood that both threads are employed. The first thread which passes through the guide 69' is engaged by 95 the needles raised by means of the lifting-cam 98 of the guide-block 87, which lifts all of the needles preparatory to being depressed by the depressing-cam 99 of the guide-block in connection with the auxiliary cam 83. As 100 the needles are thus depressed they are forced into the space 82, thus forming a loop 93 or 100 on every needle, inasmuch as at this point of the operation the pins 57 are not forced out radially. The toes of the needles 105 pass from out of the space 82 as the cam-cylinder continues to rotate onto the edge of the stitch-cam 68'. The slide-piece 79 being adjusted outwardly, it has the effect of raising the long-toed needles only to engage the 110 second thread which passes through the guide 69", and at which time the pins 57 are projected radially from the plate 52 between the needles to engage the thread and hold it to 115 make the loose back loops 94, while the needles form the shorter loops 92 between said loose back loops 94, which shorter loops 92 are enchain'd with the first thread. The toes of all the needles are next received in the channel 76, and are finally lifted to the ledge 69" 120 ready for a repetition of the operation just described.

The diagrammatic view, Fig. 12, shows the several positions of the alternate long-toed and short-toed needles, illustrating clearly 125 the manner of forming loops over the pins 57. The long-toed needles are indicated by 68 and the short-toed needles by 68".

As is well known in the art of knitting, when the heel or toe is to be formed, a portion of the needles is drawn up, and the number of needles left in action corresponds to the width of the heel or toe. The width is narrowed by raising one needle at a time from

the series employed, which is done at each reciprocation of the cam-cylinder, until only sufficient needles are left in operation to produce the narrowest course, after which the 5 needles so raised are again lowered one at a time into line with the knitting-cams to resume knitting and to widen the fabric, and the pouch for the heel and toe having been made all the needles elevated preparatory 10 to commencing the heel and toe are lowered together, in line with the knitting-cams, and circular knitting is resumed.

In the operation of my device in the reciprocating knitting only one thread is used— 15 viz., the thread which passes through the guide 69. After the requisite number of needles have been drawn out of action, as above described, the auxiliary cam 83 is lowered and the guide-block 87 thrown out of action 20 by means of the nut 88, as previously explained. A partial revolution of the cam-cylinder and shaft 21 is now given in a direction to the right of Fig. 1. As the auxiliary cam is not in operative position, of course neither 25 the long-toed nor the short-toed needles are operated thereby, as the auxiliary cam merely passes beneath the toes of all the needles without affecting any of them. When the long-toed needles are acted upon by the slide-piece 79, however, they are raised and a row 30 of the loose back loops 94 is formed, as well as the short loops 92 therebetween, for the reason that, as previously stated, the pins of the pin-supporting plate are forced out radially at this point. In other words, the 35 thread is knit into the fabric in the same manner as the second thread during the round-and-round knitting. The cam-cylinder is next given a partial turn in the opposite direction, or to the left of Fig. 1. This, as previously explained, will not revolve shaft 21, inasmuch as the dog 33 is then not in engagement with the disk 29, and consequently the 40 pins 57 are not thrown out radially. In turning the cam-cylinder to the left, also, the pin 70 of the stitch-cam 68 leaves its cam 72, and consequently said stitch-cam is dropped, while the pin 70' of stitch-cam 68' rides up its cam 72', and consequently said stitch-cam 68' is 45 raised, the parts retaining these relative positions so long as the cam-cylinder rotates to the left, for the same reasons as explained in regard to the reverse positions which they occupy when the cam-cylinder rotates to the 50 right. Inasmuch as the slide-piece 78 extends inwardly far enough to engage the short-toed needles, as well as the long-toed needles, it is obvious that all the needles are raised thereby in the rotation of the machine to the 55 left, while at the same time, inasmuch as the pins 57 are not actuated, a stitch is made without the loose back loops therein, or, in other words, the thread is knit into the fabric in the same manner as the first thread during 60 the round-and-round knitting to form the loops 93 or 100. The fabric produced by the reciprocating knitting is thus seen to be the

same as that produced by the round-and-round knitting.

In the rotation of the machine to the left in 70 the reciprocating knitting, in order to avoid all danger of the shaft 21 being rotated by the friction of the dog 33 and the friction of the apertured boss 20, I provide the dog 61, which is pivoted to the depending hub 53 of the stationary pin-supporting plate. As this dog 61 75 engages the notch 60 of the collar 54, rotation of the shaft 21 to the left by frictional contact is successfully prevented.

Figs. 13 and 14 are views in elevation and 80 plan, respectively, and on an enlarged scale, of a fabric knit upon a machine having a cam of the form just described, and also provided with my attachment. It will be seen that the fabric consists of two thread-lines, one thread-line, *a*, having a long loop 93 in one wale and a short loop 100 in the next wale, the other, *b*, floating, as at 94, behind the wales consisting of the long loops 93, but being formed into loops 92 in the other wales, which loops 90 are drawn through the short loops 100 of the other thread-line *a*, said short loops 100 being drawn through the loops 92 last formed in the other thread-line *b*. By this arrangement an inner lining composed of successive adjacent 95 lines of loose loops 94 is provided. I therefore form a fabric which possesses the maximum amount of thickness, warmth, and softness, owing to the fact that the inner loops completely cover the small interstices in the web 100 proper. The necessity, therefore, of sewing a separate lining to the fabric is avoided. Such separate inner linings are objectionable owing to the fact that they increase cost, and at the same time are apt to damage the fabric, as a sewing-needle is necessarily required in attaching such linings.

I do not wish to be understood as restricting myself in the description of the fabric and in the claims covering the same to two 110 separate threads, as, from the previous description, it will be seen that while two threads are used in round-and-round knitting, yet in the reciprocating knitting only one thread is employed. The words "thread-lines" in the description and claims should, therefore, be taken in the sense above indicated—that is, as meaning to cover either two separate threads or a single thread, in accordance as to whether round-and-round knitting is being performed or only reciprocating 115 knitting.

From the preceding description it will be seen that the special feature of my invention is the holding back of a yarn to form a series 120 of loose back loops, which loops form an inner lining completely covering the small interstices of the web proper; and furthermore that the attachment is capable of forming such loose loops when adjusted to any of the 125 ordinary forms of knitting-machines, especially good results being obtained when applied to a machine of the character described.

It is further to be noted that when the at-

tachment is applied the ordinary knit of the machine can be instantly secured, when desired, by throwing in the adjustable part 42 of the pin-cam by means of the bell-crank lever 5 46. It is obvious that when this adjustment is secured the revolution of the pin-cam casing will not operate to throw the pins out.

It will be observed that the nut 23 not only acts as a washer, but furthermore, when 10 turned, acts to raise or lower the shaft 21, and consequently raise or lower the horizontal plane of the pins 57, whereby the length of the loops formed by these pins may be regulated.

15 What I claim as my invention, and desire to secure by Letters Patent, is—

1. The combination, of a stationary needle cylinder, a revoluble cam cylinder, said cam cylinder provided with a plurality of yarn 20 guides and with a plurality of cams, a shaft, means for rotating said shaft with the cam cylinder, a pin-supporting plate, and means carried by the shaft for throwing the pins of the plate out radially at a point corresponding 25 to the point of location of one of the cams of the cam cylinder, substantially as described.

2. The combination, of a stationary needle cylinder, a revoluble cam cylinder, said cam cylinder provided with a plurality of yarn 30 guides and with a plurality of cams, a shaft, means for rotating said shaft with the cam cylinder, when said cam cylinder is rotated in one direction, and for holding said shaft stationary when the cam cylinder is rotated 35 in the opposite direction, a pin-supporting plate, means carried by the shaft for throwing the pins carried by the plate out radially at a point corresponding to the point of location of one of the cams of the cam cylinder, 40 and means for adjusting the cam which is farthest removed from the outward throw of the pins into and out of action, substantially as described.

3. The combination, of a stationary needle cylinder, a revoluble cam cylinder, said cam cylinder provided with a plurality of yarn guides, and with a plurality of cams, one of 45 said cams, when the cam cylinder is revolved

in one direction, constructed to raise every alternate needle to a position to engage one 50 of the yarns, and when said cam cylinder is revolved in the opposite direction, constructed to raise all the needles to a position to engage said yarn, a shaft, means for rotating said shaft with the cam cylinder, when said cam 55 cylinder is rotated in one direction, and for holding said shaft stationary, when the cam cylinder is rotated in the opposite direction, a pin-supporting plate, means carried by the shaft for throwing the pins of the plate out 60 radially at a point corresponding to the point of location of one of the cams of the cam cylinder, and means for adjusting the cam which is farthest removed from the outward throw of the pins into and out of action, substantially 65 as described.

4. The combination, of a cam cylinder having a lug projecting inwardly therefrom, a shaft, a casing rotatable with the shaft and having cams therein, a plate through which 70 the shaft passes freely, said plate adapted to support a series of pins, which pins are actuated by the cams, a depending part from the pin carrying plate, said depending part consisting of two sections, which when adjusted 75 together leave a slot for the reception therein of the lug of the cam cylinder, and means for adjusting the width of said slot, substantially as described.

5. A knit fabric composed of two thread 80 lines in each course, one thread line (a) having a long loop in one wale and a short loop in the next wale, as described, the other thread line (b) floating behind the wales consisting of long loops, but being formed into loops in the 85 other wales, which loops are drawn through the short loops of the other thread line (a) said short loops being drawn through the loops last formed in the other thread line (b), 90 for the purpose set forth.

In testimony whereof I affix my signature in presence of two witnesses.
